[57] CLAIM

The ornamental design for a screwdriver handle, as shown and described.

DESCRIPTION

FIG. 1 is a front elevational view of a screwdriver handle showing my new design;

FIG. 2 is a side elevational view thereof, taken at 30 degrees from FIG. 1;

FIG. 3 is a rear elevational view of FIG. 1;

FIG. 4 is a bottom plan view thereof;

FIG. 5 is a top plan view thereof; and,

FIG. 6 is a fragmentary cross-sectional view thereof, taken along line 6—6 of FIG. 1.

The broken line portions of the drawing are for illustrative purposes only and form no part of the claimed design.

FIG. 1.

FIG. 2.

FIG. 6.

FIG. 4.

FIG. 5.

FIG. 3.
